UNITED STATES PATENT OFFICE.

FRANK P. D'ARCY, OF KALAMAZOO, MICHIGAN.

BUS SEAT.

Application filed August 2, 1926. Serial No. 126,649.

This invention relates to vehicle seats, and more particularly to bus seats, and comprises all improvements over the prior art which are disclosed in this application.

5 One object is to provide a bus seat which is very yielding and comfortable.

Another object is to provide an improved leg construction which is very strong and gives improved riding comfort under the very 10 variable and severe conditions encountered in service.

Another object is to provide a reed like appearing outer covering of very marked strength and wearing qualities.

15 The above and other objects which will hereinafter appear, are attained by new and useful improvements as disclosed in this application. To enable others skilled in the art to fully understand the essential features of 20 the improvements, drawings have been annexed as a part of this disclosure.

Fig. 1 is a front perspective view of the improved bus seat.

Fig. 2 is a longitudinal vertical section 25 through one of the legs.

Fig. 3 is a rear perspective view of the bus seat.

Fig. 4 is a perspective view of the fibre covered wire.

30 The particular embodiment of the invention which is disclosed for illustrative purposes, is as follows:

A main frame 1 has secured on its underside, flange members 2 secured to universal 35 members 3 by pins 4. Universal members 3 have enlarged ball shaped lower ends 5 resting on bumper plugs 6 which latter engage the upper ends of coil springs 7 which fit neatly within vertical tube members 8 screwed into 40 base flanges 9 adapted to be secured to the floor. In sockets 10 are secured rubber bumpers 11. Screwed on the upper ends of tubes 8 are cap members 12 having openings 13 of suitable size and shape to permit universal 45 rocking of the members 3 while at the same time holding ball ends 5 in proper position within tubes 8. Rubber bumpers 11 act to

soften the stop and noise in case of a severe shock.

In addition to providing spring legs as described, two superimposed groups of spring constructions are also provided. Within frame 1 is secured a group of springs 14 of any suitable construction. Above this group are two cushions 15, 16, each having a group of springs 17 of any suitable construction. This triple spring construction provides very comfortable riding.

To provide a neat, wear resisting, strong back of reed like appearance, it is constructed 60 of steel wires 18 covered with twisted fibre, paper or the like 19.

It will be seen that the seat herein disclosed will provide for the very comfortable riding for example of a twenty five pound child on 65 one side and a two hundred pound person on the other side, without any danger of breaking the legs of the seat. Also owing to sufficient room at 13, between the parts 3 and 12, there is no binding of the leg members in action. Members 3 are of such size as to readily 70 pass down through openings 13 when the springs 7 are compressed in use.

All changes which properly come within the spirit and range of equivalency of the following claims are intended to be embraced 75 within the scope of the claims.

I claim:

1. In combination, a vehicle seat member, a floor member, four resilient supporting legs 80 extending between said members and each comprising, a housing rigidly attached to one of said members and containing a supporting spring, and means rigidly attached to the other of said members and extending into the 85 housing and having a universal bearing on the supporting spring, thereby permitting the seat to tilt down at any corner while at the same time preventing the seat from having any substantial movement parallel to the floor. 90

2. The vehicle seat of claim 1 in which the means is attached to the seat member.

FRANK P. D'ARCY.
